UNITED STATES PATENT OFFICE.

WILLIAM E. PATNAUDE, OF STOUGHTON, MASSACHUSETTS, ASSIGNOR TO THE SHALL-CROSS COMPANY, OF PHILADELPHIA, PENNSYLVANIA, A CORPORATION OF DELAWARE.

DISPENSING FAUCET.

Application filed May 13, 1925. Serial No. 29,878.

This invention relates to that class of faucets which are primarily designed for use in dispensing beverages from fountains or coolers, faucets used for this purpose being usually of the reciprocating, self closing type, to which type of faucet the present invention is primarily intended to be applied.

An important objection to faucets which have generally been used for this purpose is that after the valve is closed and the flow past the same has been cut off, several drops of the liquid dispensed will drip from the discharge orifice, this being liable to occur several minutes after the receptacle, into which the beverage was drawn, has been removed, so that it has usually been necessary to make some provision to receive the drip from the faucet, to do which is often objectionable.

The object of my invention is to provide a form of faucet which is especially adapted for dispensing purposes and which is so constructed that, the instant the flow there-thru has been cut off, no drip of liquid therefrom will occur.

I accomplish this object by means of the construction hereinafter described and as illustrated in the accompanying drawing in which:—

Figs. 1 and 2 are respectively, side and front elevations of a faucet embodying my invention.

Fig. 3 is a central vertical section thereof at line 3—3 of Fig. 2.

Fig. 4 is a horizontal sectional view at line 4—4 of Fig. 3.

Fig. 5 is bottom plan view of the discharge end thereof.

Fig. 6 is a sectional view similar to Fig. 3 of a modified form of valve casing which I may employ.

Referring to the construction of Figs. 1 to 5 the faucet casing comprises the horizontally extending inlet portion 6 and the vertically disposed cylindrical outlet portion 7, having a cap 8 threaded in its upper end. A guide pin 9 is secured to the inner side of cap 8 and depends therefrom and a cylindrically shaped valve stem 10, having a central longitudinal bore 11, which receives said pin, is provided, said stem being adapted to slide freely on said guide pin, and, as the bore of the stem is closed at its lower end, the fit of the stem on the pin is sufficiently loose to prevent the opening and closing movement

from being retarded to any greater extent than may be desired. The lower portion of the stem is provided with a cylindrically shaped head 12, having an annular groove therein, in which an elastic valve washer 13 is arranged, the portion of the head above the washer being of a diameter nearly equal to the diameter of the washer. The end wall 14 at the lower end of the casing 7 extends obliquely downward to a circular centrally disposed discharge port, and a downwardly inclined valve seat 15 is formed on the inner or upper side of said end wall which surrounds said port. The lower end portion of the head 12 is closely, but slidably fitted in said discharge port and the washer 13 is arranged to engage said seat 15 to close the passageway. An annular flange 17 is formed on the upper portion of the stem 10 and a coiled spring 18 is arranged about the guide pin 9 between the inner side of cap 8 and the upper side of said flange, in which position it will act to close the valve when opened and to press the washer 13 against its seat. An operating lever is provided for lifting the valve from its seat which comprises a handle portion 20, a shaft portion 21 which extends at right angles thereto and an arm portion 22, which extends at right angles to the shaft portion, the latter being extended through a packed bearing 23 in one side of the supply pipe 6 and the arm portion extending beneath the flange 17, so that when the handle is pushed rearwardly the valve will be lifted from its seat.

The lower end of the cylindrically shaped head 12 has a recess 12' formed therein, said recess having a concave bottom which meets the cylindrical surface of the side of the head, and forms a thin depending edge, so arranged that, when the valve, or washer 13, is resting on the seat 15, said edge on the head projects very slightly beyond the bottom surface or lowest portion of the end wall 14 of the casing or is approximately flush therewith.

The valve may be lifted from its seat by the operating lever to such an extent that the cylindrical head 12 will be completely withdrawn from the port at the lower end of the casing, so that the lower end of said head will be above the seat 15, in which position the liquid will be free to flow past the valve and be discharged through the port, and when the handle is released, so that the spring

18 may act, the head will reenter the casing port and cut off the flow before the valve actually seats, the remainder of the closing movement acting to expel any liquid which 5 might remain within the port by reason of capillary attraction after the valve is seated. As the casing surface or end wall 14 about the port converges downwardly to the edge of the port, and as this surface will be dry, no 10 liquid will run up thereon as it will be prevented from so doing by gravity and capillary repulsion, so that the extreme outer, or lower end of the head 12 is the only surface to which the liquid can cling. As the lowest 15 portion of the head is a sharp edge, drops of liquid will not cling thereto, or, if they tend to do so, they will be drawn into the cavity or recess 12' in the end of the head. That is, any drops remaining on the lower end of the 20 head will be drawn into the recess 12' either by vacuum action, or capillary attraction, and to be sustained therein by atmospheric pressure or capillary attraction for an indefinite period, as indicated in Fig. 3, so that 25 the instant the valve seats and the flow is cut off there will be no further drip from the discharge end of the faucet.

In the form of my invention above described, it is necessary to remove the cap 8, 30 and operating lever, to secure access to the valve, so as to renew the valve washer, should it be necessary to do so. In the construction of Fig. 6 the entire upper portion of the casing 25 is formed in one piece and a removable lower end portion 26 is provided, having a 35 threaded connection with the upper portion, which, when removed, permits ready access to the valve washer, so that it may be changed. The construction, so far as the means for preventing dripping is concerned, is the same 40 as that already described.

I claim:

1. A self-closing dispensing faucet comprising a vertically disposed cylindrically shaped casing having a side entrance pipe and a discharge port at its lower end, a vertically movable hollow valve stem having a valve at its lower end arranged to seat on the casing 45

about the port, a guide spindle mounted in said casing and entering said hollow stem to 50 guide the same, an operating lever having a shaft portion mounted in the wall of said pipe, said shaft portion having an arm extended at an angle thereto and engaged with said stem to lift the same when said lever is 55 operated, and a closing spring surrounding said guide spindle and acting against the said casing and said stem to close the valve against its seat.

2. A self-closing dispensing faucet comprising a vertically disposed cylindrically shaped casing having a side entrance pipe and a discharge port at its lower end, a vertically movable hollow valve stem having a valve at its lower end arranged to seat on the casing about the port, a guide spindle mounted in said casing and entering said hollow stem to 60 guide the same, an outwardly projecting flange on the upper end of said hollow stem, a closing spring surrounding said guide spindle and acting against the said casing and the said stem and flange to close the valve against its seat, an operating lever having a shaft portion mounted in the wall of said pipe, said shaft portion having an arm extending at an 65 angle thereto and engaging with said flange to lift the said stem when said lever is operated.

3. A self-closing dispensing faucet comprising a casing having a side entrance pipe and a discharge port at its lower end, a vertically movable hollow valve stem in said casing and having a valve at its lower end arranged to seat in the casing about the port, a guide spindle entering said hollow stem to 70 guide the same, a cap adapted to close the upper end of said casing and provided with means to support said guide spindle, a spring surrounding said guide spindle and acting against the said cap and said stem to close the valve against its seat, and means operable from the exterior of said casing to engage said stem and lift the same.

In testimony whereof, I have signed my name to this specification.

WILLIAM E. PATNAUDE.
